UNITED STATES PATENT OFFICE.

MALCOLM TARLTON PHILLIPPS, OF TOORAK, SOUTH AUSTRALIA, AUSTRALIA.

SANITARY FLUSHING DEVICE.

Application filed January 5, 1922. Serial No. 527,210.

To all whom it may concern:

Be it known that MALCOLM TARLTON PHILLIPPS, a subject of His Majesty the King of Great Britain, and citizen of the Commonwealth of Australia, residing at Watson Avenue, Toorak, in the State of South Australia, Commonwealth of Australia, has invented certain new and useful Improvements in Sanitary Flushing Devices, of which the following is a specification.

My invention relates to an improved sanitary flushing device, the object of the same being to provide a device for the purpose indicated which shall be comparatively simple and inexpensive in construction and is controlled by an air valve, the associated parts of the construction being somewhat similar to those which are at present in use, except that the flushing cover device does not rise and fall as is usually the case, thus enabling the cistern to be protected or screened by wire netting or other means.

In carrying my invention into effect I use a suitable cistern wherein the usual water supply is fitted and controlled by a floating ball valve. The cistern is furnished with a tubular shaped outlet which is surrounded by a concentric wall, and above this part of the construction I provide a cylindrical shaped cover having a concentric inner wall, the arrangement being such that when the parts are in working position the concentric inner wall of the cover is external to the tubular outlet and the outer wall of the cover is external to the inner cylindrical wall. The cover which is stationary serves as an air lock and is connected by means of a pipe or tube with air release apparatus, and a snifter pipe is fitted in the cover and connected with the upper portion or air space of the appliance. The inflowing water which is controlled by the action of the floating ball valve enables the water to rise in the cistern and to charge the space enclosed by the cover up to a pre-determined level where it is retained until released by the release of air and is thus discharged through the outlet pipe.

But in order that my invention may be more clearly understood I will now proceed to describe the same by aid of the accompanying illustrative drawings wherein:

Fig. 1 is an isometrical view of the cistern and its associated parts in part section.

Fig. 2 is a sectional elevation of a cylin-

drical cover as manufactured from cast metal.

Fig. 3 is a sectional elevation of portion of the cistern as made from cast metal showing the outlet and its concentric wall. 60

Fig. 4 is a plan of a portion of the cylindrical cover showing modified arrangement for fitting the snifter pipe.

Fig. 5 is an outline diagram illustrating the approximate water levels when an air 65 lock has been formed.

In each of the illustrations similar letters of reference are used to denote similar or corresponding parts wherever they occur.

In the drawings *a* is the cistern which may be manufactured from sheet metal, earthenware, or cast metal and is fitted with a tubular shaped outlet pipe *b*, the extension of which is continued above the floor of the cistern as indicated at *c*, and is surrounded by a concentric inner wall of similar height as shown at *d*. These portions may be constructed from cast metal substantially as illustrated in Fig. 3 of the drawings, the outlet pipe *b* of Fig. 1 being screwed or 80 otherwise attached to the underside of the cistern as will be readily understood upon reference to Fig. 3 of the drawings.

This portion of the structure is enclosed by a flushing cover preferably of cylindrical shape the top portion of which is shown at *e*, and the outer wall *f* of the cover is of sufficient diameter to enclose the corresponding internal wall in the cistern, the inner wall *g* of the cover being interposed between 90 the previously mentioned walls of the cistern.

The cover does not actually rest on the floor of the cistern but is supported by legs *h* which may be attached in any convenient 95 manner as indicated in Fig. 1 or may form a portion of the casting as shown in Fig. 2.

In like manner the internal portions *c* and *d* do not extend to or come into contact with the portion *e* but leave a small clearance space corresponding approximately with the space formed by the legs between the bottom of the cover and the floor of the cistern. 100

In any convenient position on the cover I 105 mount a snifter pipe or valve *j* which extends through the outer wall near to the top and communicate with the air space which is formed immediately below the cover plate *e*, its lower end protruding downwards to a position near to the bottom 110 of the wall *f*.

In Figs. 2 and 4 I have shown a recess formed in the periphery of the outer wall for the accommodation of the snifter pipe indicated at j' . This arrangement enables 5 the pipe to be fitted into a screw-threaded hole at j^2 thus enabling it to easily be elevated or depressed for adjustment purposes.

From the top of the roof or cover I extend an air pipe k having an outlet l at its 10 lower end which may with advantage be fitted with an india-rubber seating. This constitutes an outlet valve for the air which may be closed by any convenient means as for instance by the plate m which is supported on a hinge pin n and is pressed against the outlet of the air pipe by the spring o , the operation being effected by the press button p thus enabling the air to be discharged through the pipe from the 15 underside of the cover thus causing syphonic action so that the water is easily discharged through the portions b and c .

The method of fitting this apparatus can be varied according to requirements, and 20 the water supply is of an ordinary nature consisting preferably of the inlet pipe q which is fitted with an ordinary valve r against which the lever s of the floating ball presses as the water rises or releases when 25 the water falls, but I provide an extension pipe t below the valve the bottom portion of which extends towards the floor of the cistern thus reducing or eliminating the noise 30 which would otherwise be caused by the inflowing water.

It will be understood that the cover does not rise and fall as is at present the custom with the majority of flushing cisterns now in use but may be regarded as a fixture but 35 it is easily accessible for inspection or repair by disconnecting it from the air pipe k which leaves it free to be lifted. This arrangement enables the whole of the water tank to easily be covered with a wire gauze 40 covering u or other cover.

The situation of the water inlet is such that the water can rise above the top plate 45 of the cover, and consequently presses upon

the air which is imprisoned therein thus preventing the outflow by syphonic action, 50 until the pressure is released by the outlet of air through the valve and pipe as previously described.

From the foregoing description it will readily be seen that the cistern is put into 55 action by opening the air pipe k . When the cistern is in action and the water is being discharged the snifter pipe allows the air to enter and thus stops the syphonic action before the outgoing water falls to the level of 60 the bottom of the cover thereby minimizing the noise which would otherwise be caused by the complete emptying of the cistern. The general principle described in the foregoing paragraph is already well-known.

Having now fully described and ascertained my said invention, and the manner in which it is to be performed, I declare that 70 what I claim is:—

1. In a sanitary flushing device of the character described, a cistern, a discharge pipe extending into said cistern, a concentric upright wall surrounding said discharge pipe, a cover comprising a flat top 75 piece and concentric depending walls adapted to nest about said pipe and upright wall, the outer of said depending walls having an axial depression extending almost to the flat top piece, and a snifter pipe in said 80 depression, the outer end of which extends through the closed end of the depression to establish communication between the outside of the depending wall and the inside space directly beneath the cover piece. 85

2. In a sanitary flushing device of the character described, the combination of elements as set forth in claim 1, the opening in the closed end of the depression being threaded, and the upper end of the snifter 90 pipe being threaded to engage said opening to allow vertical adjustment of the snifter pipe by rotation thereof.

In testimony whereof he hath affixed his signature.

MALCOLM TARLTON PHILLIPPS.
